UNITED STATES PATENT OFFICE

ERIC R. KARGER, OF LOS ANGELES, CALIFORNIA, ASSIGNOR TO THE UNION LITHOGRAPH CO., INC., OF LOS ANGELES, CALIFORNIA, A CORPORATION OF CALIFORNIA

DESIGN FOR A SAFETY PAPER

Application filed January 11, 1932. Serial No. 42,442. Term of patent 14 years.

To all whom it may concern:

Be it known that I, ERIC R. KARGER, a citizen of the United States, residing at Los Angeles, in the county of Los Angeles, State of California, have invented a certain new, original, and ornamental Design for Safety Paper, of which the following is a specification, reference being had to the accompanying drawing.

The figure of the drawing illustrates a piece of safety paper embodying my design.

I claim:

The ornamental design for a safety paper, as shown.

ERIC R. KARGER.
